LOOM ATTACHMENT

Herbert Hugh Hughes, Columbus, Ga., assignor to Swift Manufacturing Company, Columbus, Ga., a corporation of Georgia.

Application July 17, 1941, Serial No. 402,826

8 Claims. (Cl. 139—340)

The present invention relates to loom attachments, and more particularly to certain improvements in cut measurers and signals for textile weaving machinery.

In the textile trade, cloth is generally sold on a yardage basis, that is in continuous definite lengths because of certain well known advantages.

An object of the present invention is to secure measuring of such definite length in that the loom is automatically stopped at the completion of this definite length which is generally referred to as a "cut"; and the invention also contemplates that a signal, preferably a visual signal, be given as to the cause of loom stoppage in order that the loom attendant or operator shall not be deceived as to the cause of such stoppage.

Modern looms are equipped with a variety of stop motions for the purpose of stopping the loom in certain eventualities, such for instance as the breaking of the warp thread. Stoppage under such conditions requires a repair. As a result, as soon as the loom is stopped the loom fixer or attendant begins to examine the stalled machinery for defects or deficiencies to repair in order that the operation of the loom may be resumed at the earliest practicable moment.

It is therefore an object of the invention to provide in connection with the warp stop motion a signal device for showing immediately to the attendant that the stoppage of the loom was not occasioned by any cause demanding repair but only by completion of the requisite linear yardage; to the end that the attendant may rapidly put the loom back into weaving performance.

Another object of the invention is to utilize the electric stop motion now found in standard equipment on conventional looms on which to base extension circuits including a controller and switches for causing this standard stop motion to be actuated on the production of the required "cut."

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a perspective view of an improved cut measurer and signal, constructed in accordance with the present invention and shown coupled to the sandroller of a loom, indicated in chain lines.

Figure 2 is also a perspective view of the improved cut measurer and signal, as seen from an opposite end, illustrating the gearing and also the sand roller, the latter being broken away.

Figure 3 is a top plan view, on an enlarged scale, and with parts broken away, of the improved cut-measurer and signal.

Figure 4 is a central vertical section taken longitudinally through the same on the line 4—4 in Figure 3.

Figure 5 is a horizontal central section taken on the line 5—5 in Figure 4.

Figure 6 is a vertical cross section taken on the line 6—6 in Figure 4.

Figure 7 is a similar view taken on the line 7—7 in Figure 4.

Figure 8 is a fragmentary perspective view of one section of the automatic circuit controller with both member switches in open position.

Figure 9 is a front elevation looking from the right in Figure 8 with the control plunger retired and the two member switches both closed.

Figure 10 is a similar view showing the subsequent phase in which control plunger is in advance position prying open both member switches.

Figure 11 is a cross section taken on the line 11—11 in Figure 9, and

Figure 12 is a diagrammatic view including circuit diagram showing the wiring of the improved device to the standard circuit of a loom.

Referring more particularly to the drawings, in Figure 1 there is shown in dotted or chain lines a conventional form of loom of which the sandroller is designated at 15.

As shown in Figures 1 and 2, the sandroller 15 is equipped with a pinion 16 fast thereon disposed in mesh with a gear wheel 17, which in turn meshes with a pinion 18. The pinions 16 and 18 and the gear wheel 17 form a suitable gear train for communicating the rotary motion of the sandroller 15 to the improved cut measurer and signal which is housed for convenience in a container 19 affixed in any suitable manner to the loom frame adjacent one end of the sandroller 15.

Still referring to Figures 1 and 2, the top of the container 19 is shown as having a window 20, covered by plain or lens glass or other translucent material through which a visual signal is displayed for the attention and information of the loom attendant or operative; and exposed externally of the container 19 is the handle 21 of a manual switch operable by such attendant as hereinafter described.

Referring more particularly to Figures 3 to 7 inclusive, 22 designates a shaft mounted through an end wall of the casing 19 upon the external end of which the pinion 18 is made fast and upon the inner end of which is fixedly secured a pinion 23 meshing with the initial gear 24 of a gear reduction unit constructed as follows:

The initial gear 24 is loosely mounted on the shaft 25 and has fast therewith a single-tooth gear 26. At each revolution of gears 24, 26, the tooth 27 encounters star wheel 28 loose on shaft 29 and rotates the same one step. Star wheel carries with it pinion 30 which is disposed in continuous mesh with a second gear wheel 31 of the reduction train. This second gear wheel 31 and its single-tooth gear 32 are loose on the shaft 25. At each rotation of the gears 31, 32, the single-tooth 33 will engage and rotate one step a second star wheel 34 which, with its associated pinion 35 is mounted for loose rotation on the shaft 29. Pinion 35 meshes with the third gear wheel 36 of the reduction train which carries fast with it the single-tooth gear 37 having the tooth 38 meshing with star wheel 39, the pinion 40 of which meshes with the last gear wheel 41 of the reduction train. This last gear wheel 41 loosely rotates about shaft 25 and has affixed to the side thereof a cam disc 42.

As shown in Figure 6, the cam disc has a shoulder or step 43 and a peripheral edge which progresses in a volute curve from the bottom of the shoulder at one side around the disc in a clockwise direction to the high point of the shoulder at the other end of the volute curve.

The reduction gear employed may be of any suitable form and supported and driven in any appropriate manner. Such reduction gear may be composed of any suitable number of gear units other than the three units herein shown and described. I find this form of gear reduction, producing as it does, very small movement in the cam disc 42 comparatively to the revolution rate of the sandroller 15, to be convenient and suitable for the purposes of this invention.

Due to the freedom of the various gear wheels upon shaft 25, detents 44 are preferably engaged therewith to arrest rotation of a casual or accidental nature, but yielding to permit the enforced rotation of the parts under the compulsion of the enmeshed gear train. The gear reduction unit may be mounted upon a frame 45 installed as a unit within the container 19.

The cam disc 42 operates as a controller for automatic switches which govern the stoppage of the loom and the illumination of the lamp 46 housed within the container 19 below the window 20.

As shown in Figures 4, 6 and 7, plungers 47 and 48 arranged vertically one above another at diametrically opposite sides of the cam disc 42 bear at their inner ends against the volute peripheral curve of the disc and are guided in their reciprocating movements, incident to the rotation of the disc 42 by the horizontal arms 49 of a vertically disposed frame 50 which may be affixed to the gear reduction frame 45 or to any other appropriate support in the container 19.

Referring more particularly to Figures 8 to 11 inclusive, one plunger 47 with its member switches is disclosed, the unit on the diametrically opposite side of the disc being substantially identical.

The plunger 47 has a rounded or tapering outer nose 51. Such nose fits between the longer spring

contact bars 52 and 53 which are biased by inherent resilient action to move together to close against their short companion contact bars 54 and 55. The presence of the nose 51 in a projected position, as shown in Figure 8, causes spring fingers or contact bars 52 and 53 to be expanded or pried apart from their companion bars 54 and 55, thus opening both switches. The contact bars 52 and 54 form one member switch and the contacts 53 and 55 form the other member switch of the unit at one side of the cam disc.

The outer portions of the contact bars are segregated between insulating plates 56 and the entire double switch unit may be carried by and attached in any suitable way to a carrier member 57 extending from a plate 58 which plate extends alongside the arm 49 of the frame 50. The binding posts or connecting strips for the switches are indicated at 59 for contact 52, 60 for 54, 61 for contact 55 and 62 for contact 53.

Flaring jaws 61 on the spring contact bars 52 and 53 extend axially toward and along the nose 51 and are inclined and rounded for the purpose of better cooperating with a more extensive surface of the conical or conoidal surface of the nose 51.

Referring more particularly to Figure 12 the opposite plunger 48 moves in and out between spring contact bars 62 and 63 which form member switches with shorter contact bars 64 and 65. These various contact bars are insulated from one another by insulating blocks 66. The blocks and intervening contacts are secured together in any suitable way and affixed to a carrier member 67. The binding posts 68, 69, 70 and 71 are respectively for the contacts 62, 64, 65 and 63.

Further referring to Figure 12, the manual switch, the handle 21 of which projects on the exterior of the casing 19, is constructed as follows:

The handle or button 21 is a part of an insulating body 72 mounted to slide back and forth horizontally in a cradle or support 73 suspended from a plate or escutcheon 74 affixed by appropriate fastenings 75 to the top of the container 19. The cradle or support 73 is let in through an opening 76 in the top of the casing and the handle or button 21 of the switch projects up through a slot 77 in the plate 74. The switch body carries contacts 78 and 79 movable over selected fixed contacts 80, 81, 82, 83, 84, 85 supported in the cradle 73 and having rounded upper heads placed in alignment and in juxtaposition. The contacts 78 and 79 are of a width to close against two adjacent fixed contact members. The movable contact 78 may be a flat disc projected outwardly by a spring 86 enveloping the stem 87 of the contact 88 which parts are all mounted for reciprocation in a cavity 88 in the insulating body 72.

The other contact member 79 is preferably in the form of a ball, the contour of which conforms to the incurved surfaces formed between adjacent fixed contact members, the construction and arrangement being such that the ball 79, under the influence of the spring 89, forms a detent tending to hold the movable part 72 of the manual switch in the adjusted position until forcibly shifted. The ball 79 and its spring 89 are mounted for movement in a cavity 90 of the insulating body 72.

The manual switch is capable of movement to two positions, one of which is shown in Figure 12 in which the ball 79 engages fixed contacts 80

and 81 and the other movable contact 78 engages fixed contacts 83 and 84. In the other or left hand position of the switch the ball 79 will engage contacts 81 and 82 while the flat movable contact 78 will engage fixed contacts 84 and 85. Thus in either position of the manual switch fixed contacts 81 and 84 will be closed; in one position of the switch with the respective contacts 80 and 83; in the other position of the switch with the contacts 82 and 85.

Referring particularly to Figure 12, the power is brought in through the usual mains, for instance at 550 volts A. C. to the transformer 91 which steps the current down, for instance to 12 volts A. C. This is in accordance with customary usage in loom practice to provide electric current for the stop motion of the loom. Such stop motion includes the stop motion bar 92 and the drop wires, one of which is indicated at 93, having eyes 94 for the passage of the thread. A lead 95 electrically connects the stop motion bar 92 with electro-magnet 96. The electro-magnet 96 controls the piece 97 which is connected indirectly with the knock-off handle 100 of the loom.

Also in accordance with standard practice the electromagnet 96 is connected by lead 98 with the circuit breaker switch 99 which is connected in the usual manner to the shifter handle 100 of the loom which controls the operation thereof.

In accordance with the present invention, I tap into the existing stop motion circuit by connecting the stop motion bar by lead 101 to the fixed contact 84 of the manual switch, while the other lead 102 of the main supply circuit is connected by the branches 103 and 104 with the binding posts 68 and 59 respectively on the opposite controller units. The binding post 69 at one side of the controller is connected by the lead 105 with fixed contact 80 of the manual switch, while the binding post 60 at the other side of the controller is connected by the lead 106 to the fixed contact 82 of the manual switch.

The binding posts 161 and 76 are grounded as indicated. The binding post 162 is connected by lead 107 with the fixed contact 85 of the manual switch, while at the other side of the controller the binding post 71 is connected by the lead 108 with the fixed contact 83 of the manual switch. A lead 109 connects one side of the lamp 46 or other signal with the fixed contact 81 of the manual switch. The other side of the lamp 46 is grounded as indicated.

The piece 97 actuated by electromagnet 96 is connected indirectly with the knock-off handle 100 of the loom. This member 97, when thrown up by electro-magnet 96 comes in contact with a projection 110 on the lay of the loom. A spring 111 connects the handle 100 with the circuit breaker switch 99.

In operation, the main circuit for operating the loom is closed in the customary manner by the shifter lever 180. The loom continues in operation weaving the cloth. Incident to this operation the sandroller 15 is being continuously rotated and the revolutions thereof incident to the weaving of a predetermined length or yardage of cloth is calculated with reference to the gear reduction unit whereby after such predetermined linear amount of cloth has been woven the cam disc 42 will have been rotated through one-half revolution or through an angular distance of 180°. The cam disc 42 is so timed that the high point 43 of the cam will move out of contact with the involved plunger 47 or 48 at

the time when the predetermined yardage has been completed. The inner movement of the plunger which follows this release allows the associated switches to close. The diametric opposite point of the cam disc engaging the opposite plunger at substantially this time thrusts such opposite plunger outwardly to cause opening of its associated switches at the other side of the controller.

Assuming the parts in the position illustrated in Figure 12 with the manual switch 21 shifted to the right hand position, with the high point of the cam shoulder 43 beneath plunger 48 forcing it outward to maintain open the member switches 62, 64 and 63, 65; the opposite plunger 47 being at a low point of the cam so that it is forced inwardly by spring pressure of the member switches allowing the member switches 52, 54 and 53, 55 to close. The closed condition of these last mentioned member switches however does not affect the operation of the loom nor the illumination of the signal lamp 46 due to the fact that the manual switch has been moved to the right hand position, disconnecting the circuit of member switch 53, 55 at the open fixed contact 85 of the manual switch, and disconnecting the circuit through the closed member switch 52, 54 through the fixed contact 82 of the manual switch, which fixed contact 82 is unconnected with either of the movable contacts 78 or 79. As a matter of fact the closed position of the member switches 52, 54 and 53, 55, in a previous operation, had stopped the loom and illuminated the signal lamp 46, and having thus fulfilled their function, these closed member switches were rendered further ineffective by the loom attendant in shifting the manual switch 21 from the left hand position, which it occupied in the former eventually, into the right hand position it is seen to occupy in Figure 12, thus opening the previously closed circuits at the fixed contacts 82, 85 as just explained.

Thus in opening these previously closed control circuits the loom attendant has at his command, through the manual switch, an agency to immediately place the loom in condition for a resumption of operation without interference from the continued closed condition of the circuits through the member switches 52, 54, and 53, 55.

In moving the manual switch to suspend operation of the member switches 52, 54 and 53, 55 at one side of the cam disc 42, the loom attendant simultaneously, and by the same action, places the member switches 62, 64 and 63, 65 at the opposite side of the cam disc 42 in a potential position to close the loom circuit causing loom stoppage and the illumination of the signal lamp 46 at the next completion of the required linear yardage of cloth woven. When the manual switch is shifted to the right in Figure 12 the right hand plunger 48 is in a projected position and the member switches 62, 64 and 63, 65 are thus open. Therefore the loom may continue in operation until the shoulder 43 moves off the plunger 48 and allows the plunger to move inwardly by the spring action of the resilient contact bars 62 and 63. When that occurs the member switches at the right side of the controller will be closed.

The closing of the member switch 62, 64 establishes the circuit from the supply line 102, branch 103, binding post 68, switch contacts 62, 64, binding post 69, lead 105 to the manual switch to and through contacts 80, 79 and 81, and by

lead 109 to the lamp 46 and its ground. At the same time the other member switch closes a circuit from the transformer secondary through the circuit breaker switch 99, leads 98, 95, 101 to the manual switch, through contacts 84, 78 and 69 thereof, lead 103, binding post 71, member switch 63, 65 and binding post 73 to ground thus causing the operation of the shifter lever 100 to cause stoppage of the loom.

As the high point 43 of the cam disc 42 rotates past the inner end of the right hand plunger 48, such plunger is driven radially inward by the spring action of the contacts 62 and 63 and switches 62, 64, 63, 65 promptly close. The switches will remain closed until the disc 42 rotates an angular distance to bring the high point of the cam again beneath plunger 48. This will occur after approximately 180° revolution of the disc 42. During this long interval the operation of the loom must be resumed and the signal light 46 extinguished. Therefore the closed member switches 62, 64 and 63, 65 must, immediately after the performance of their function in stopping the loom at the required yardage and giving the signal thereof to the operator of this reason for loom stoppage, be rendered ineffective; and this is accomplished by the arrangement of the manual switch, the handle 21 of which is exposed externally of the casing 19 for the movement by the hand of the loom attendant. By shifting such manual switch to the left in Figure 12 the member switches at the right hand side of the controller are simply cut out of all connection with the loom operating circuit and with the signal lamp circuit. In doing this the manual switch re-establishes the potentiality of the other member switches at the left hand side of the device, which during the interval have been moved to open position by the rotation of the cam disc 42 to a point where the plunger 47 is thrust radially outward a sufficient distance to pry the contact bars 52 and 53 to an expanded open position.

As soon as one plunger falls off the shoulder 43, the cam disc is so constructed that the other plunger is moved to switch opening position, whereby the loom attendant may immediately shift over the manual switch to enable him to re-establish loom operation and extinguish the signal light.

The lens or window 20 in the casing 19 above the signal lamp 46 may be in color, for instance red, to more effectively attract the attention of the operator or loom attendant and the illumination of the lamp or of the window or its lens 20 is an indication to the loom attendant that the loom stoppage has occurred because of completion of the predetermined linear yardage of cloth woven rather than because of any other cause of loom stoppage. Such loom attendant is therewith put on notice that otherwise the loom is functioning properly and orderly and he therefore has no need to examine the loom for possible defects occasioning stoppage.

The extension loom stoppage circuits as well as the lamp circuit, the controller and the manual switch are all contained as a unit in the case 19 from which only the two leads 101 and 102 extend, the one to the stop motion bar 92 and the other to the secondary of the transformer 91 by-passing the circuit breaker switch 99.

It is obvious that various changes and modifications may be made in the details of construction and design of the above specifically described embodiment of this invention without departing

from the spirit thereof, such changes and modifications being restricted only by the scope of the following claims:

What is claimed is:

5. In a loom having an electric stop motion, extension electric means connected to the stop motion for causing loom stoppage when a predetermined "cut" has been woven and comprising a controller having means driven from the loom and a plurality of sets of movable switch members controlled in their opening and closing movements by said last-named means for actuating the electric stop motion, a manual switch in circuit with said switch members and the electric stop motion for controlling the potentiality of the sets of switch members to cause loom stoppage through the stop motion, and signal means in circuit with said manual switch and said switch members.
10. 2. In a loom having an electric stop motion, means to utilize said stop motion for stopping the loom when a predetermined "cut" of cloth is woven comprising extension circuits forming continuations of the electric stop motion, a plurality of automatic switches in said circuits, means driven by the loom to cause opening and permit closing of said automatic switches alternately, a manual switch in circuit with the automatic switches and stop motion to select the automatic switch which at any given time energizes the electric stop motion and a signal in circuit with said manual and automatic switches.
15. 3. In a loom having an electric stop motion, means to stop the loom and display a signal when a predetermined "cut" has been completed comprising a plurality of extension stop circuits connected to the electric stop motion in operative relation thereto, signal means, signal circuits therefor, a controller for controlling the opening and closing of the stop circuits to potentially cause loom stoppage through the electric stop motion, and a manual switch included in all said circuits for selectively governing the same.
20. 4. In a loom having an electric stop motion and a rotating shaft, means to stop the loom and display a signal when a predetermined "cut" has been completed comprising a plurality of extension stop circuits connected to the electric stop motion in operative relation thereto, signal means, signal circuits therefor, a controller for controlling the opening and closing of said stop and signal circuits, a reduction gear for driving said controller from the loom shaft, and a manual switch included in all said circuits for selectively governing the same.
25. 5. In a loom having an electric stop motion and a rotating shaft, means to stop the loom and display a signal when a predetermined "cut" has been completed comprising a plurality of extension stop circuits connected to the electric stop motion in operative relation thereto, a signal, signal circuits for said signal, member switches in said stop and signal circuits, a controller driven by the loom shaft and comprising a cam, and plungers associated for movement by said cam and in operative positions to control the opening and closing of said member switches, and a manual switch included in all said circuits for selectively governing the same.
30. 6. In a loom having an electric stop motion, means to stop the loom and display a signal when a predetermined "cut" has been completed comprising a plurality of extension stop circuits connected to the electric stop motion in operative relation thereto, signal means, signal circuits for

said signal means, pairs of member switches, one switch of each pair in one of the stop circuits and the other switch of the pair in one of the signal circuits, said member switches being biased to closed position, one switch pair angularly offset from another switch pair, a loom-driven controller constructed and arranged to open the switch pairs alternately at stated intervals of loom operation, and a manual switch in all said stop and signal circuits so constructed and arranged as to control the completion of the stop and signal circuits through each member switch pair and to open said circuits of any pair after the same have been allowed by said controller to close.

7. The combination of claim 6, in which the controller comprises movable members having tapered parts to enter between and pry apart

5 spring contacts of the member switches, said spring contacts reacting on said tapered parts to eject the members and allow closing of the member switches.

8. The combination of claim 6, wherein said member switches comprise spring contacts pre-disposed together, and said controller comprises a rotary cam and reciprocatory plungers moved out by said cam, said plungers having tapered noses positioned to be projected between said spring contacts to force same apart to open the member switch pairs, said spring contacts reacting on said tapered noses to drive the plungers inwardly and allow of closing of the member switch pairs so soon as the high point of the cam passes a plunger.

HERBERT HUGH HUGHES.
